FIRE EXTINGUISHING SYSTEM

Walter A. Beach, Chicago, Ill., assignor to Cardox Corporation, Chicago, Ill., a corporation of Illinois

Application October 25, 1945, Serial No. 624,410

11 Claims. (Cl. 169—9)

1

This invention relates to fire extinguishing systems employing carbon dioxide as the extinguishing medium and more particularly to the control system for regulating the delivery of this medium.

In general, the present fire extinguishing system is based on the method disclosed and claimed in the patent to Eric Geertz, Number 2,143,311, issued January 10, 1939. That system employs a storage tank of large capacity in which liquid carbon dioxide is maintained at a low temperature and a correspondingly low pressure. The liquid carbon dioxide stored in this manner may selectively protect a plurality of independent hazards each of which is supplied with liquid carbon dioxide through a branch pipe from a header connected to the storage tank.

The branch pipes which extend from the header to the individual hazards to be protected are controlled by separate selector valves. It is possible to operate a system in which the header and the branch pipes are under the pressure of the supply tank so that delivery upon any desired hazard may be accomplished by merely opening the proper selector valve. However, it is preferable that the header and branch pipes be under no pressure as this reduces the requirement that the pipe connections and selector valves be gas-tight. It is, therefore, preferable to employ a master valve in the header close to the supply tank and which is normally closed. When a selector valve in one of the branch pipes is then opened to discharge liquid carbon dioxide, it is consequently necessary that the master valve in the header be opened.

It is impractical for an attendant to manually open the proper selector valve and then go to the master valve in the header, because of the time which would be lost, particularly if these valves were spaced at considerable distances. The systems which have been devised, therefore, include a control means generally involving an electrical circuit which will automatically open the master valve when a selector valve is opened. However, such a system involves the disadvantage that the master valve may remain open for an unnecessary length of time, because the attendant forgets to shut it off.

If the master valve is allowed to remain open for too long a period, the liquid carbon dioxide may become fully spent. This is wasteful and in view of the expense of liquid carbon dioxide it is important that some means be provided to shut off the master valve after it has discharged liquid carbon dioxide for a period which should be sufficient to extinguish the fire in the particular

2

hazard which is being protected. The invention, therefore, provides means for automatically closing the master valve after a predetermined time interval so that the contents of the supply tank may not be exhausted.

Another feature of the invention is the provision of an electrical relay which controls the opening and closing of the master valve and which is initiated by an opening movement of a selector

10 valve.

A further feature of the invention involves the provision of an electrical relay which controls the master valve and which includes a lock-out portion which prevents a repetitive operation of the relay until the selector valve has been closed.

Other features of the invention will be apparent during the course of the following description when considered with the accompanying drawings.

20 In the drawings:

Figure 1 is a schematic representation of a fire extinguishing system embodying this invention.

Figure 2 is an elevational view of a selector valve and its associated electrical switch.

25 Figure 3 is a schematic wiring diagram of a modified electrical circuit, and

Figure 4 is a schematic wiring diagram of another modified electrical circuit.

In Figure 1 three different fire hazards are shown and they are represented by the chambers 10, 11 and 12. Each one of these chambers is provided with a discharge orifice or nozzle 13, 14 and 15, respectively, by which the chamber may be flooded with carbon dioxide to extinguish the fire. However, it is to be understood that the invention is not limited in this respect as more or fewer chambers may be protected by discharge orifices. Moreover, the system may be applied equally as well to hazards which are not in confined spaces, but which are objects subject to fire and which are in the open and upon which the carbon dioxide may be directly played. In addition, the invention is not limited to the size of the hazard to be protected, but may be applied 30 in any one system to hazards of quite different sizes.

The storage tank 16 contains the liquid carbon dioxide which is to be discharged from the orifices 13, 14 and 15. The carbon dioxide in container 16 is preferably maintained at a low temperature and its corresponding low vapor pressure, in accordance with the disclosure of the aforementioned patent issued to Eric Geertz. The invention is not restricted to the size of this 35 particular storage tank as it may be of fairly

small size only sufficient to effectively handle a single fire or it may be of quite large size so that a single fire will only partly exhaust it.

The liquid carbon dioxide in the storage tank 16 is delivered therefrom by means of a dip tube or pipe 17 which extends close to the bottom of the tank. The discharge from the dip tube 17 is controlled by a manually operable shut-off valve 18 and also by a master control valve 19 following valve 18. The manually operable shut-off valve 18 is normally open and is provided for the principal purpose of cutting off the remainder of the system when repairs or changes are to be made in one of the other valves or the piping.

Valve 18 may be of the type disclosed in detail in Figures 3, 4 and 5 of Patent 2,356,990, issued to Charles A. Getz, on August 29, 1944. The master control valve 19 may be of the type illustrated in Figures 6, 7 and 8 of the aforementioned patent to Charles A. Getz. The master control valve 19 is intended to normally be closed so that it confines the carbon dioxide in the storage tank 16. It is important, therefore, that this valve 19 be "bubble-tight."

From the master control valve 19 leads a header 21 and connected to this header are branch pipes 22. The discharge from each branch pipe 22 is controlled by a selector valve 23 each of which passes carbon dioxide to one of the discharge orifices 13, 14 and 15. As the selector valves 23 may be of the same construction, they are given the same reference numeral.

The details of the master control valve 19 are explained more fully in the aforementioned patent to Charles A. Getz, but it may be mentioned here that it is opened and closed as a result of the development of differential fluid pressure conditions within its casing. A pilot valve is provided to control this development of differential fluid pressure conditions and this pilot valve is operated by an electrical control device to which the lead lines 24 and 25 are connected. When the electrical control device associated with valve 19 is energized by means of the lead lines 24 and 25, the master control valve will be opened. In like manner, when the supply of current by lead lines 24 and 25 is interrupted to de-energize the electrical control device, the valve 19 will move to closed position.

As is schematically indicated in Figure 1 and is shown in somewhat more detail in Figure 2, the selector valves 23 in branch pipes 22 have associated therewith an electrical switch 26. The electrical switch 26 is actuated upon manual movement of the valve 23 so that when the valve 23 is moved to open position the switch 26 associated therewith is moved to closed position.

As is shown in Figure 2, the valve 23 is manipulated by means of a handle 27 connected to the valve shaft 28. Attached to this valve shaft 28 is a cam member 29 which is located to contact a push button 30 of the switch 26. When the valve 23 is closed the cam 29 is positioned apart from the contact button 30 so that the switch 26 is open, but when shaft 28 is turned by handle 27, the cam member 29 is brought into engagement with the button 30 to close switch 26. It will be appreciated, however, that the arrangement shown in Figure 2 will operate satisfactorily if the elements are reversed. That is, if the switch 26 is of the type which is closed when the button 30 is released and is opened when it is depressed, it will be merely necessary to position the cam 29 so that it will be in contact with the button 30 when the valve 23 is in closed position.

Switches 26 may be supported in the proper position in any desired manner. As here shown, this is accomplished by means of brackets 31 carrying the switches 26 and attached to branch pipes 22.

From the switches 26 extend lead lines 32 and 33 to circuit wires 34 and 35, respectively. As a consequence, the switches 26 and their lead lines 32 and 33 are in parallel across the circuit wires 34 and 35 so that a connection will be established between the wires 34 and 35 by the opening of any one of the selector valves 23. Circuit wires 34 and 35 could be connected directly to lead lines 24 and 25 of the master control valve 19 with the interposition of a source of electric current so that the master control valve 19 would be under the direct control of the selector valves 23. However, in accordance with the invention, a relay indicated at 36 is interposed between the circuit wires 34 and 35 and the lead lines 24 and 25 so that the master control valve 19 is under the control of the relay 36.

As will hereinafter appear, the relay 36 serves to directly control the opening and closing of the master control valve 19 and the switches 26 merely serve to initiate this control exerted by the relay 36. After such initiation of the control exerted by relay 36 by closure of one of the switches 26, the switch 26 is locked out of the circuit so that the relay 36 completely takes over control and will maintain the master control valve 19 open and will close it after a predetermined time limit. After the valve 19 has been closed by the relay 36, the relay 36 will continue to lock-out the switches 26 so that a repeated opening of the master control valve 19 cannot be effected until the closed switch 26 is opened to thereby reset the relay 36 for another operation. To open this closed switch 26, the selector valve 23 associated with it must be closed.

The electric power input to the relay 36 and the associated electrical circuits is through supply lines 37 and 38. The supply line 38 is connected to the circuit line 34. The other circuit line 35 is connected to the contacts 42 and 43 of a solenoid operated switch 44.

The contact 45 of switch 44 is connected to contact 42 by switch 44 when it is in its lower or normal position, and this contact 45 is joined to a timing device here represented by motor 46. The other side of motor 46 is connected to supply line 37. When one of the contacts 26 is closed, therefore, a circuit is established from supply line 38, circuit lines 34 and 35, contacts 42 and 45 of switch 44, motor 46 and supply line 37. The motor 46 is therefore set into operation.

Motor 46 controls the movement of three switches, indicated at 47, 48 and 49 which are normally open. The switches 47, 48 and 49 may, for example, be operated by cams on a shaft driven at a reduced speed by motor 46. Rotation of motor 46 will cause these switches to close and, after a predetermined time, to open.

A "time cycle controller" of the type described above is disclosed in the patent to Joseph H. Staley, No. 2,141,024.

Switches 47 and 48 are connected to the electric input wire 38. The other contact 51 of switch 48 is connected to motor 46 so that when switch 48 is closed by rotation of motor 46, the motor 46 will be supplied with current through switch 48. The motor will be maintained in operation by switch 48, therefore, even though

the switch 44 breaks the connection between contacts 42 and 45.

To cause switch 44 to move upwardly and break the connection between contacts 42 and 45, the solenoid 52 which operates switch 44, is supplied with current by the closure of switch 47. One side of solenoid 52 is connected to contact 53 of switch 47 and its other side is connected to supply line 31. When motor 46 causes switch 47 to be closed, solenoid 52 will therefore be energized and lift switch 44 to break the connection between contacts 42 and 45. This will serve to lock out of the circuit the control exerted by switches 26 over the operation of motor 46.

It is desirable that solenoid 52 remain energized to maintain switch 44 in its upper position after switch 47 is opened, in the event that a switch 26 remains closed. For this purpose switch 44, when it is lifted, closes a connection between contacts 43 and 54, the contact 54 being connected to solenoid 52. When switch 26 is initially closed and sets motor 46 in operation, solenoid 52 is thereafter energized by switch 47 as well as by switch 44 through contacts 43 and 54. However, when switch 47 is broken by continued rotation of motor 46, solenoid 52 continues to be energized by switch 44 through its contacts 43 and 54 so long as the closed switch 26 remains closed.

As long as switch 26 remains closed, therefore, switch 44 will be held up and motor 46 cannot start another operation, as the contacts 42, 45 remain broken. When the closed switch 26 is thereafter opened, due to closure of its associated selector valve 23, solenoid 52 will be de-energized and the switch 44 will fall to connect contacts 42 and 45 so that the system will be in readiness for the next operation.

Switch 49 is closed when switches 47 and 48 are closed. The switch 49 is connected to lead line 24 to master valve 19, and its contact 55 is connected to contact 51 of switch 48. Lead line 25 of master valve 19 is connected to supply line 37. When switches 48 and 49 are closed, current is then delivered through these switches from supply line 38 to the master valve 19.

Switch 48, therefore, supplies current both to motor 46 and to master valve 19. As the master valve 19 also is controlled by switch 49 it is possible to have the switch 49 opened before the switch 48 is opened. Thus, by varying the cam which closes switch 49, this switch 49 can be caused to open at a period of time before motor 46 has made the complete cycle necessary to open switch 48 and stop motor 46. In this way, the period of time that valve 19 is open, may be varied.

In the operation of the system, it is intended that an attendant open the proper selector valve 23 when he sees a fire which is to be put out by the discharge orifice 15 to which that selector valve 23 is connected. Such manual opening of the proper selector valve 23 will close the associated electrical switch 26 to close a circuit between the circuit lines 34 and 35. This will serve to start rotation of the motor 46 through the contacts 42, 45 of switch 44. After the actuation of relay 36 has been initiated in this manner, the relay 36 will take over operation due to the fact that motor 46 will close the switches 47, 48 and 49. Closure of switch 49 will maintain energization of motor 46. Closure of switch 47 will energize solenoid 52 to lift switch 44 and connect contacts 43 and 54. Closure of switch 49 will supply electrical energy to the control device of valve 19

to thereby effect its opening movement. Liquid carbon dioxide will, therefore, flow through the valve 19 through the header 21 and pass the particular one of the selector valves 23 which has been open.

Valve 19 will remain open until motor 46 has rotated far enough to cause the switches 47, 48 and 49 to open. This will break the circuit to the control means of valve 19 so that this valve 19 will close and shut off the supply of carbon dioxide even though the selector valve 23 which was opened remains open. The relay 36 will not, however, cause a repeated opening of valve 19 even though the switch 26 is held open by the still open valve 23 because the solenoid 52 will remain energized, because the contacts 43 and 54 will be closed as the switch 44 is held in an upward position. Therefore, the circuit to the control means of valve 19 will remain open until the valve 23 which was open is closed, as this will open the associated switch 26 so that the circuit supplying solenoid 52 with electrical energy will be broken. The switch 44 will, therefore, fall and will close the contacts 42 and 45, but motor 46 will not now rotate because the switches 26 will all be open. When one of the valves 23 is thereafter opened and its associated switch 26 is closed, the motor 46 will be supplied with current through the closed contacts 42 and 45 and the system will operate in the manner which has been described.

The circuit of Figure 3 is similar to that of Figure 1, except that switch 49 has been eliminated and lead line 24 from the electric control means of master valve 19 is connected to contact 45. With this arrangement, current will be supplied directly to the control means of valve 19 by the closure of a switch 26, through closed contacts 42 and 45. As motor 46 will at the same time be set into operation, current will continue to be supplied to the control means of valve 19, by the closure of switch 48, and valve 19 will remain open until switch 48 is opened. As with the circuit of Figure 1, switches 26 will be locked out by switch 44 until the opened selector valve is closed and switches 26 are all open.

In the circuit of Figure 4, switch 49 is connected directly to supply line 38 and contact 55 of this switch is connected to lead line 24 of the control means of valve 19. The control means of valve 19 therefore receives current directly from line 38, through closed switch 49, instead of through both switches 48 and 49 as in the circuit of Figure 1. With this circuit of Figure 4, the time that valve 19 is open may be varied by changing the cam which controls switch 49.

What I claim is:

1. A fire extinguishing system for protecting a plurality of separate hazards, comprising a storage tank for supplying liquid carbon dioxide, a discharge pipe extending from the tank, a master valve for controlling the flow of carbon dioxide through the discharge pipe, a header connected to the outlet of the master valve, a separate branch pipe line extending to each hazard from the header, a selector valve adapted only to be manually opened and closed for controlling each branch pipe, electrical means operable in response to the opening operation of any selector valve while the remaining valves are closed for effecting opening operation of the master valve, means for effecting closure of the master valve after a predetermined time interval irrespective of the subsequent position of the selector valve after initial opening of the master valve, and

means to prevent reopening of the master valve while any of the selector valves are open.

2. A fire extinguishing system for protecting a plurality of separate hazards, comprising a storage tank for supplying liquid carbon dioxide, a discharge pipe extending from the tank, a master valve for controlling the flow of carbon dioxide through the discharge pipe, a header connected to the outlet of the master valve, a separate branch pipe line extending to each hazard from the header, a selector valve adapted only to be manually opened and closed for controlling each branch pipe, electrically operated means associated with said master valve for controlling its opening and closing operations, a circuit controlling means associated with each selector valve to be operated upon manipulation of the selector valve, an electric connection between said electrically operated means and said circuit controlling means to effect opening of the master valve when one of the selector valves is opened while the remaining valves are closed, said connection including a timing device for limiting the time period that the master valve remains open although the selector valve remains open for a longer period of time, and means for breaking said electric connection to prevent reopening of the master valve while any of the selector valves are open.

3. A fire extinguishing system for protecting a plurality of separate hazards, comprising a storage tank for supplying liquid carbon dioxide, a discharge pipe extending from the tank, a master valve for controlling the flow of carbon dioxide through the discharge pipe, a header connected to the outlet of the master valve, a separate branch pipe line extending to each hazard from the header, a selector valve adapted only to be opened and closed manually for controlling each branch pipe, electrically operated means associated with said master valve and which when energized will effect opening of the valve, an electric switch associated with each selector valve to be closed upon opening of the selector valve, and an electric connection between said electrically operated means and said electric switches to cause opening of the master valve when one of said switches is closed by opening movement of a selector valve while the remaining valves are closed, said connection including means to break the electrical connection after a predetermined time interval to thereby deenergize said electrically operated means and effect closure of the master valve although the selector valve remains open for a longer period of time, and means to prevent the reclosing of said electrical connection and the reopening of said master valve while any of the selector valves are open.

4. A fire extinguishing system for protecting a plurality of separate hazards, comprising a storage tank for supplying liquid carbon dioxide, a discharge pipe extending from the tank, a master valve for controlling the flow of carbon dioxide through the discharge pipe, a header connected to the outlet of the master valve, a separate branch pipe line extending to each hazard from the header, a selector valve adapted only to be opened manually for controlling each branch pipe, electrically operated means associated with said master valve for controlling its opening and closing operations, a circuit controlling means associated with each selector valve to be operated upon opening of the selector valve, and an electric connection between said electrically operated means and said circuit controlling means to effect

opening of the master valve when one of the selector valves is manually opened while the other selector valves remain closed, said connection including a relay responsive to said circuit controlling means and controlling current flow to said electrically operated means, and said relay including means for taking over control of current flow to the electrically operated means and eliminating control by said circuit controlling means to effect closing of the master valve after a predetermined time interval even though the selector valve remains open for a longer period of time, and means for maintaining control of said current flow by said relay to prevent reopening of said master valve while any of the selector valves are open.

5. A fire extinguishing system for protecting a plurality of separate hazards, comprising a storage tank for supplying liquid carbon dioxide, a discharge pipe extending from the tank, a master valve for controlling the flow of carbon dioxide through the discharge pipe, a header connected to the outlet of the master valve, a separate branch pipe line extending to each hazard from the header, a selector valve adapted only to be opened manually for controlling each branch pipe, electrically operated means associated with said master valve for controlling its opening and closing operations, an electric circuit for said electrically operated means including a timing device for maintaining the master valve open a predetermined time and then effecting its closure, means operated by opening of one selector valve while the remaining valves are closed for initiating the functioning of said electric circuit, and means to prevent the refunctioning of said electric circuit to reopen said master valve while any of the selector valves are open.

6. A fire extinguishing system for protecting a plurality of separate hazards, comprising a storage tank for supplying liquid carbon dioxide, a discharge pipe extending from the tank, a master valve for controlling the flow of carbon dioxide through the discharge pipe, a header connected to the outlet of the master valve, a separate branch pipe line extending to each hazard from the header, a selector valve adapted only to be opened manually for controlling each branch pipe, electrically operated means associated with said master valve for effecting opening of that valve when the electrically operated means is energized, an electrical circuit for energizing said electrically operated means and including timing means for deenergizing the electrically operated means after a predetermined time to effect closure of the master valve, means operated by opening operation of one selector valve while the remaining valves are closed for initiating the functioning of said electric circuit, and means to prevent the reenergizing of the electrically operated means to reopen said master valve while any of the selector valves are open.

7. A fire extinguishing system for protecting a plurality of separate hazards, comprising a storage tank for supplying liquid carbon dioxide, a discharge pipe extending from the tank, a master valve for controlling the flow of carbon dioxide through the discharge pipe, a header connected to the outlet of the master valve, a separate branch pipe line extending to each hazard from the header, a selector valve adapted only to be opened manually for controlling each branch pipe, electrically operated means associated with said master valve for controlling its opening and closing operations, a circuit controlling means

means associated with each selector valve to be operated upon opening of the selector valve, and an electric connection between said electrically operated means and said circuit control means to effect opening of the master valve when one of the selector valves is opened while the other valves remain closed, said connection including a timing device for limiting the time period that the master valve is open and also including means for breaking the connection to said circuit controlling means to prevent reopening of said master valve while any of the selector valves are open.

8. A fire extinguishing system for protecting a plurality of separate hazards, comprising a storage tank for supplying liquid carbon dioxide, a discharge pipe extending from the tank, a master valve for controlling the flow of carbon dioxide through the discharge pipe, a header connected to the outlet of the master valve, a separate branch pipe line extending to each hazard from the header, a selector valve adapted only to be opened manually for controlling each branch pipe, electrically operated means associated with said master valve for controlling its opening and closing operations, a circuit controlling means associated with each selector valve to be operated upon opening of the selector valve, and an electric connection between said electrically operated means and said circuit controlling means to effect opening of the master valve when one of the selector valves is opened while the other valves remain closed, said connection including a relay responsive to said circuit controlling means and controlling current flow to said electrically operated means, said relay including a timing device to limit the time period that the electrically operated means functions to hold the master valve in its open position, and said relay including a solenoid operated switch which in normal position closes a circuit from the circuit control means to said timing device and which in its abnormal position opens the circuit from the circuit control means to said timing device and closes a circuit from the circuit controlling means to the solenoid to retain the switch in its abnormal position while any of the selector valves are open.

9. A fire extinguishing system for protecting a plurality of separate hazards, comprising a storage tank for supplying liquid carbon dioxide, a discharge pipe extending from the tank, a master valve for controlling the flow of carbon dioxide through the discharge pipe, a header connected to the outlet of the master valve, a separate branch pipe line extending to each hazard from the header, a selector valve adapted only to be opened manually for controlling each branch pipe, electrically operated means associated with said master valve for controlling its opening and closing operations, a circuit controlling means associated with each selector valve to be operated upon opening of the selector valve, an electric connection between said electrically operated means and said circuit controlling means to effect opening of the master valve when one of the selector valves is opened while the other valves remain closed, said connection including a relay responsive to said circuit controlling means and controlling current flow to said electrically operated means, said relay including a timing device to limit the time period that the electrically operated means functions to hold the master valve in its open position, said relay further including a solenoid operated switch which in normal position closes a circuit from the circuit control means to said timing device and which in its abnormal position opens the circuit from the circuit control means to said timing device and closes a circuit from the circuit controlling means to the solenoid to retain the switch in its abnormal position while any of the selector valves are open.

in normal position closes a circuit from the circuit control means to said timing device and which in its abnormal position opens the circuit from the circuit control means to said timing device and closes a circuit from the circuit controlling means to the solenoid to retain the switch in its abnormal position while any of the selector valves are open; and said relay also including a switch closed by operation of said timing device to energize the solenoid and thereby eliminate control of the relay by said circuit controlling means.

10. A fire extinguishing system for protecting a plurality of separate hazards, comprising a storage tank for supplying liquid carbon dioxide, a discharge pipe extending from the tank, a master valve for controlling the flow of carbon dioxide through the discharge pipe, a header connected to the outlet of the master valve, a separate branch pipe line extending to each hazard from the header, a selector valve adapted only to be opened manually for controlling each branch pipe, electrically operated means associated with said master valve for controlling its opening and closing operations, a circuit controlling means associated with each selector valve to be operated upon opening of the selector valve, an electric connection between said electrically operated means and said circuit controlling means to effect opening of the master valve when one of the selector valves is opened while the other valves remain closed, said connection including a relay responsive to said circuit controlling means and controlling current flow to said electrically operated means, said relay including a timing device to limit the time period that the electrically operated means functions to hold the master valve in its open position, said relay further including a solenoid operated switch which in normal position closes a circuit from the circuit control means to said timing device and which in its abnormal position opens the circuit from the circuit control means to said timing device and closes a circuit from the circuit controlling means to the solenoid to retain the switch in its abnormal position while any of the selector valves are open, and said relay also including a switch to continue the operation of the timing device once it has been initiated by retaining said solenoid operated switch in its abnormal position until the predetermined time period has elapsed.

11. A fire extinguishing system for protecting a plurality of separate hazards, comprising a storage tank for supplying liquid carbon dioxide, a discharge pipe extending from the tank, a master valve for controlling the flow of carbon dioxide through the discharge pipe, a header connected to the outlet of the master valve, a separate branch pipe line extending to each hazard from the header, a selector valve adapted only to be opened manually for controlling each branch pipe, electrically operated means associated with said master valve for controlling its opening and closing operations, a circuit controlling means associated with each selector valve to be operated upon opening of the selector valve, an electric connection between said electrically operated means and said circuit controlling means to effect opening of the master valve when one of the selector valves is opened while the other valves remain closed, said connection including a relay responsive to said circuit controlling means and controlling current flow to said electrically operated means, said relay including a timing device to limit the time period that the electrically

operated means functions to hold the master valve in its open position, said relay further including a solenoid operated switch which in normal position closes a circuit from the circuit control means to said timing device and which in its abnormal position opens the circuit from the circuit control means to said timing device and closes a circuit from the circuit controlling means to the solenoid to retain the switch in its abnormal position while any of the selector valves are open, said relay also including a switch closed by operation of said timing device to energize the solenoid and thereby eliminate control of the relay by said circuit controlling means, and another switch to continue the operation of the timing device once it has been initiated by retaining said solenoid operated switch in its ab-

normal position until the predetermined time period has elapsed.
